UNITED STATES PATENT OFFICE.

EDWARD TODD, JR., OF NEW YORK, N. Y.

DESIGN FOR A PENCIL-POINT PROTECTOR.

SPECIFICATION forming part of Design No. 31,073, dated June 27, 1899.

Application filed May 15, 1899. Serial No. 716,963. Term of patent 7 years.

To all whom it may concern:

Be it known that I, EDWARD TODD, Jr., a citizen of the United States, residing at New York city, in the county of New York and State of New York, have invented and produced a new and original Design for Pencil-Point Protectors; and I do declare the following to be a full, clear, and exact description of the invention, such as will enable others skilled in the art to which it appertains to make and use the same.

The drawing is a perspective view of a pencil-point protector, showing my new design.

As therein shown, the leading feature of my design is a tubular structure having about one-half of its length cylindrical and the remainder expanded by easy curves into a bul-

bous form. The cylindrical portion is slit lengthwise for a part of its length, and the end of this portion is left open to admit the pencil. The opposite end of the protector is closed by an ornamental head having beads, grooves, and a rounded end.

Having thus described my invention, what I claim, and desire to secure by Letters Patent, is—

The design for a pencil-point protector, substantially as herein shown and described.

In testimony whereof I affix my signature in presence of two witnesses.

EDWARD TODD, JR.
